UNITED STATES PATENT OFFICE.

ETHAN I. DODDS, OF CENTRAL VALLEY, NEW YORK, ASSIGNOR TO HENRY F. GILG, OF PITTSBURGH, PENNSYLVANIA.

METAL CAR END.

Application filed September 24, 1926. Serial No. 137,510.

This invention relates to pressed sheet metal ends for railway box cars.

The objects of the invention are to provide a sheet metal car end of a configuration which can be produced by die pressing and which will secure maximum stiffening of the plates from which it is formed, with reinforcement in all directions against the bending and wrinkling strains to which car ends are exposed. A further object is to make the car end in substantially duplicate parts, so that one set of dies may be used for forming the several portions of a multi-part car end. Other uses and advantages of the invention will be apparent from the following specification.

Referring to the drawings, Fig. 1 is an elevation and front view of the car end as applied; Fig. 2 is an under plan view; Fig. 3 is a side elevation; Fig. 4 is a section on the line IV—IV of Fig. 1; and Fig. 5 is a section on the line V—V of Fig. 1.

For a number of reasons it is desirable to have sheet metal ends for ordinary wooden box cars. Many different forms of pressed plates have been employed for this purpose, the plates being pressed between dies to form corrugations, ribs, and other reinforcing configurations therein, for the purpose of giving rigidity to the end wall. It is for the same general purposes well-known in the art that the present structure is designed.

Referring to the drawings, the car end illustrated is made up of an upper plate 1 and a lower plate 2, joined together on a horizontal meeting line by overlapping flanges 3 and 4 at the meeting edges of the plates 1 and 2, respectively. These flanges are connected by rivets 5, so that in effect the two plates are formed into an integral structure. Except for a slight difference in the flanges 3 and 4, to permit one to seat on top of the other, the plates 1 and 2 are identical and interchangeable. They may therefore be made from a common die, with a slight modification formed by a subsequent operation, to produce the necessary difference in the flange height.

The flanges 3 and 4 are raised from the base plane of the plates, and when riveted together form an effective reinforcing rib extending horizontally across the car end. Vertical reinforcing ribs 6 and 7 extend from the upper and lower edges of the two

plates to the middle point thereof, as illustrated in Fig. 1. These ribs taper from the base plane of the plate at the upper and lower edges to the height of the flanges 3 and 4 at the middle portion. This is illustrated at the left of Fig. 4, which is in part a vertical section along the rib 7.

Diagonal reinforcing ribs 8, 8, and 9, 9, are provided in each of the plates, extending from the outer corners thereof to the middle, and tapering upward from the plane of the plates to the height of the median rib formed by the flanges 3 and 4. The structure of one of these diagonal reinforcing ribs 8 is illustrated at the right of Fig. 4, 70 and in end view at the middle of Fig. 2.

By the ribs 6, 7, 8, and 9, and the rib formed by the interfitting edges joined by rivets 5, the car end is divided into eight similar right triangles. All of these ribs are 75 transverse in the sense that they extend across from edge to edge of the car end. The portion of the plate enclosed between the dividing ribs and the outer edges of the car structure is formed in the pressing operation into a pyramid having sloping triangular faces *a*, *b*, and *c*.

The sides of the plates are turned down to form side flanges 10 for attachment to the side frames of the car body.

It will be observed that the structure illustrated and described divides the car end into four quarters, each of which is bounded on the two inner sides by a raised reinforcing rib. Each quarter is individually divided diagonally by a raised reinforcing rib, the two halves of each quarter of the diagonal being stiffened by pressing the plate area between ribs into a pyramidal shape. This arrangement gives great stiffness, while at 90 the same time furnishing a structure that can be formed in two or four parts, or even in one part, by pressing properly sized plates between forming dies. There will be some drawing of the plates in this die forming operation, and that will result in maximum stiffness of the finished structure as will be readily understood by those familiar with the art.

I claim:

1. A car end formed of pressed metal plates comprising reinforcing ribs extending through the middle point and at right angles to the sides thereof additional reinforcing ribs constituting diagonals of the 110

car end and raised pyramidal portions bounded by the diagonals and rectangular cross ribs.

2. A car end formed of pressed metal plates comprising reinforcing ribs extending through the middle point of the car end and at right angles to the sides thereof and reinforcing ribs constituting diagonals of the car end the portions of the plates between the said reinforcing ribs being raised and drawn into pyramidal form to give stiffness to the area so enclosed.

3. A car end formed of pressed metal plates, divided into a plurality of triangles by transverse reinforcing ribs the triangular intermediate portions being pressed to pyramidal form.

4. A car end formed of pressed metal plates, comprising reinforcing ribs extending through the middle point of the car end and at right angles to the sides thereof, and reinforcing ribs constituting diagonals of the car end and raised pyramidal portions bounded by the diagonals and median cross ribs, the diagonals and the vertical median rib tapering from the outer edges to a maximum height at the middle portion of the car end.

5. A car end formed of pressed metal plates comprising transverse reinforcing ribs and raised pyramidal portions positioned in the spaces between said ribs.

In testimony whereof I sign my name.

ETHAN I. DODDS.
